[57] CLAIM

The ornamental design for a braking assembly for preventing paper from unrolling too rapidly, as shown and described.

DESCRIPTION

FIG. 1 is a top plan view of a braking assembly for preventing paper from unrolling too rapidly showing my new design;

FIG. 2 is a front elevational view thereof;

FIG. 3 is a left side elevational view thereof;

FIG. 4 is a right side elevational view thereof;

FIG. 5 is a bottom plan view thereof;

FIG. 6 is a rear elevational view thereof; and,

FIG. 7 is a top, front, and left side perspective view thereof.

The broken-line disclosure of the support in the views is for illustrative purposes only and forms no part of the claimed design.

FIG.1
